HOUSING

Henry William Betzler, Rutherford, N. J., assignor
to Federal Telephone & Radio Corporation,
New York, N. Y., a corporation of Delaware

Application December 5, 1942, Serial No. 467,951

3 Claims. (Cl. 175—366)

1

This invention relates to housings for electrical apparatus and has for its principal objects to provide a housing which can be easily and quickly assembled and disassembled and through which a cooling fluid may be made to flow.

It is often desirable to place electrical apparatus such as stacks of plate type rectifiers in a housing and it may also be desirable to pass a cooling fluid such as air through the housing. It is sometimes necessary to open the housing quickly to inspect or repair the apparatus and for this purpose the housing should be of simple construction and one which can easily be assembled and disassembled.

In accordance with this invention there is provided a housing of which the several parts are made to fit together and the assembly of which is secured by a relatively small number of fastening devices such as nuts and bolts. The invention will be more fully understood from the following detailed description when considered in conjunction with the drawings of which:

Fig. 1 is a perspective view of a housing in accordance with this invention;

Fig. 2 shows the housing of Fig. 1 with two of the walls removed to show the interior;

Fig. 3 is a cross-sectional view taken at line 3—3 of Fig. 1; and

Fig. 4 is a cross-sectional view of a detail taken at line 4—4 of Fig. 1.

Referring to the drawings, the housing comprises the two oppositely located sides 1 and 2 and the top and bottom members 3 and 4, forming a prism. One of the end members 5 is composed of a square or rectangular frame work 6 holding a screen 7 through which air may blow. The other end member comprises a funnel 8 having its enlarged end fitted against one edge of the sides 1, 2, 3 and 4 and of the same outside dimensions as the frame 6. The small end of the funnel terminates in a ring 9 of dimensions adapted to fit with a pipe or source of cooling air. The top and bottom plates 3 and 4 comprise bent over side portions, 13, 13' and 14, 14', respectively, which cover corresponding edges of the side walls 1 and 2 and hold them in place, as shown in Fig. 3.

The rear edges of the side, top and bottom plates are provided with curved grooved portions, 15, 16, 17 and 18, and the front edges of these side, top and bottom plates are provided with curved grooved members which are identified by the same numbers primed. The curved grooved members are adapted to fit over the rounded edges 11 of the frame work 6 of the rear screen and of the funnel member 8 at the front as shown,

2

so that when the overhanging portions 13, 13' and 14, 14' of the top and bottom plates are fitted over the corresponding side plates, all the grooved members are firmly held against the corresponding rounded edges of the frames 6 and 12. As shown in Figs. 1 and 4, the grooved portions 17, 18 and 17', 18' of the lateral sides 1 and 2 do not extend all the way to the top and bottom edges of the sides 1 and 2, but merely meet the corresponding overhang of the top and bottom members 3 and 4. The assembly is finally secured by means of studs 19, of which six are shown, extending through the housing from top to bottom and through the top and bottom plates, these being secured by corresponding nuts and locknuts indicated by 19'. By this arrangement the top and bottom plates and the side plate are firmly secured to the rear end member 5 and to the frame of the front funnel member 8 and the only fasteners required are the relatively few number of nuts on the studs.

The housing is especially well adapted for use with electrical apparatus which can be mounted on the studs, such as the plate type rectifier stack shown in Fig. 2. There are shown three stacks 20, 21 and 22, although it will be understood that any other number of stacks of rectifier plates, or stacking arrangements, could be used. The individual rectifier elements in the stack may be of any well known construction. The particular construction of the elements and also the stacking arrangement is shown in application Ser. No. 464,748, filed November 6, 1942.

Only one of these plates, namely plate 23 is shown in detail. This comprises a flat base plate ordinarily of iron or steel or aluminum which may or may not be nickel coated, covered by a layer of selenium 24, on top of which there is placed a metallic counter-electrode 25. A contact member 26 is held in contact with the counter-electrode member by means of a spring member 27 which is held against the contact member by means of a rivet 28 which passes through and fastens on the other side of the plate, with suitable insulating washers such as 29 for the purpose of preventing short circuiting of the contact member to the base plate. A tab 30 from the flat contact plate 26 is carried over to a conducting washer 31 at the edge of the plate, making electrical contact with the washer 31. The washer and the tab 30 are suitably insulated from the base plate 23 by means of insulating washers and material to prevent short circuits. Any number of these rectifier elements is then connected in a stack by passing the stud through the corresponding wash-

ers 31 of each element, and the adjacent washers are held in contact with each other by screwing down the nut 32. The opposite terminals of the elements are similarly arranged, these terminals being integral with the respective base plates themselves. They are provided with similar washers 31 placed over an ear of the base plate 23 and through which the corresponding stud passes. The screwing down of the top and bottom nuts compresses all of the washers at the individual stacks against each other to make contact between adjacent washers. Thus the individual elements in the stack are connected in parallel with each other.

It is possible to divide off each main stack 20, 21 and 22 into separate groups to provide desired circuit arrangements and connections. The particular grouping shown is for a 3-phase bridge connection. The bus bars 33 and 34 make connections with the proper groups in each stack and form the D. C. terminals for the rectifier circuits, the terminal members 35 and 36 respectively passing out through suitable slits 37 and 38 in an insulating strip 39 which is screwed over an opening in the side wall 1 by means of screws 40. The alternating current input terminals for the bridge rectifier circuit are not shown in Figs. 1 and 2, but one of the three required terminals 41 is shown in Fig. 3, this being connected to stack 21. There will be two other terminals connecting to stacks 20 and 22 respectively.

An air pipe is adapted to be connected to the ring member 8 for blowing a blast of air or other cooling fluid through the stack between the elements thereof and out of the rear screen 7.

This construction provides a light, simple, compact housing for a rectifier which is adapted to provide cooling and thereby enable high current to be transmitted. The housing can likewise be very quickly assembled and disassembled for repairs and inspection.

What is claimed is:

1. A combination rectifier, housing and interconnection device for said rectifier, including a plurality of stacks, each formed of a plurality of individual rectifier elements, a housing enclosing said stacks and comprising four lateral walls and two end walls forming a prism, a first pair of oppositely located lateral walls having portions adapted to engage the corresponding peripheral portions of said end members and a second pair of lateral walls having overhanging portions which overhang the first pair of lateral walls, a plurality of studs holding together each stack and serving to interconnect the individual recti- 55

4

fier elements thereof and also holding together said second pair of lateral walls, and a plurality of relatively flat bus-bar-like members having apertures through which said studs pass so as to connect therewith, said bus-bar-like members being also provided with lateral tabs extending outwardly through said first pair of lateral walls, whereby external connection with predetermined groups of rectifier units other than those connected together by said studs, is made possible, said first pair of lateral walls being provided with suitable insulation and narrow slots where-through said tabs project, so that a substantially air tight closure of said slots by said tabs is secured.

2. A housed rectifying unit comprising a plurality of rectifier stacks each including a mounting member projecting from each stack end, a housing enclosing said stacks including a pair of ends and four lateral walls forming a prism, means engaging the mounting members for supporting said stacks from each of a first pair of opposite lateral walls, and means interconnecting the end margins of an opposite pair of lateral walls and the contiguous margins of said ends for holding said ends in place, and released by removal of one of said first pair of walls to permit removal of said ends.

3. A combination rectifier, housing and interconnection device for said rectifier, including a plurality of stacks, each formed of a plurality of individual rectifier elements, a housing enclosing said stacks and comprising four lateral walls and two end walls forming a prism, a first pair of oppositely located lateral walls having portions adapted to engage the corresponding peripheral portions of said end walls and a second pair of lateral walls having overhanging portions which overhang the first pair of lateral walls and also having means to engage and hold the corresponding peripheral portions of said end walls, a plurality of studs holding together each stack and serving to interconnect the individual rectifier elements thereof, and also holding together said second pair of lateral walls, and a plurality of conductor devices having flat portions through which the studs pass and are connected therewith, and terminals to extend to the outside of the housing for connection with other apparatus, certain lateral walls being provided with openings through which said terminals extend, and with insulation around said openings to provide substantial air tight closure.

HENRY W. BETZLER.
